INTERNAL COMBUSTION ENGINE

Fred L. Knowles, Fort Dodge, Iowa

Application April 18, 1942, Serial No. 439,601

7 Claims. (Cl. 123—80)

My invention relates to improvements in internal combustion engines of the rotary sleeve valve type.

The invention is designed with the principal object in view of providing a high speed, high compression, cool running engine, capable of maximum power output at both low and high altitudes with a minimum of friction and operating parts and with lower fuel consumption than present day internal combustion engines.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in longitudinal section of an internal combustion engine constructed in accordance with my invention.

Figure 2 is a view in transverse vertical section taken on the line 2—2 of Figure 1.

Figure 3 is a detail view in horizontal section taken on the line 3—3 of Figure 1.

Figure 4 is a similar view taken on the line 4—4 of Figure 1.

Figure 5 is a detail view in top plan of two contiguous cylinder heads and parts related thereto.

Figure 6 is a view in vertical longitudinal section taken through one of the oil separators.

Figure 7 is a view in transverse section taken on the line 7—7 of Figure 6.

Figure 8 is a similar view taken on the line 8—8 of Figure 6.

Figure 9 is a view in bottom plan of one of the cylinder heads.

Figure 10 is a view in horizontal section taken through one of the pistons.

Figures 11 to 17 are diagrammatic views illustrating the operations occurring in different phases of a single cycle of operation of the crank shaft and one piston.

Referring now to the drawings by numerals, my improvements have been shown therein as embodied in a four-cycle, four-cylinder in line engine. The crank case of the engine comprises, as is usual, the upper and lower sections 1, 2 bolted together, as at 3, and provided with end bearings, as at 3', for the crank shaft 4, the cranks 5 of which are arranged in the usual angular relation in a four-cycle engine, that is to say, with the pair of end cranks 5 arranged opposite in 180° angular relation to the pair of

intermediate cranks. The crank shaft 4 carries at its rear end the usual starter gear 6. Intermediate the cranks 5 the crank shaft 4 is constructed and arranged to provide diametrically enlarged hollow portions, as at 7, journaled in intermediate bearings 8 provided in the crank case and suitably formed for assembly with the crank shaft.

Wrist pins 9 connect the lower ends of the connecting rods 10 to the cranks 5. The connecting rods 10 are provided with upper ball-like ends 11 forming part of ball and socket joints in the lower ends of reciprocating pistons 12.

The pistons 12 comprise concave heads 13, axial pedestal cores 14 depending from said heads and carrying the sockets 15 of the ball and socket joints, radial cooling fins 16 extending between the pedestal core 14 and the inner walls of the pistons, and narrow cooling fins 17 extending from said wall intermediate the fins 16, all as best shown in Figure 10. The pistons 12 are provided with suitable piston rings 18 and work in tubular sleeve valves 19 rotatable in cylinders 20 arranged in line and in spaced relation in a cylinder block 21 bolted, as at 22, on top of the upper section 1 of the crank case.

The cylinder block 21 is of hollow honeycomb construction and at the ends thereof and intermediate the cylinders 20 embodies suitable vertical cooling fins 23, as shown in Figure 4.

The cylinder heads 24 also form heads for the sleeve valves 19. Each cylinder head 24 is of dished form with an upper edge flange 25 fitting in the top of the cylinder 20 and is threaded into the upper end of the related sleeve valve 19 with its flange 25 fitting in the upper end of the cylinder 20 and bearing on top of said sleeve valve 19. A packing ring 26 is mounted in the flange 25 to form a seal between the same and the cylinder 20. Each cylinder head 24 is formed with a reduced upwardly tapering center dome 27 into the top and center of which the spark plug 28 is threaded and which forms an upwardly tapering compression chamber 29 in said head. Thus, a uniformly shaped combustion chamber is provided in the head with the spark plug equidistant from all parts of the top of the piston.

Radial spirally arranged fins 30 rise from each head 24 and extend out over the cylinder 20 in arrangement such that under rotation of the heads 25 air is blown by said fins up around the cylinders through the fins 23. A vertical tube 31 is set into the fins 23 of each head, above the dome 27, to house the spark plug 28 and down which air is sucked by the fins 30 thereby

further maintaining the heads 24 cool also to cool said spark plug.

The sleeve valves 19 are rotated by reduction gearing at one-fourth the speed of rotation of the crank shaft 4.

The reduction gearing comprises a pair of like bevel gears 32, 33, one fast on the crank shaft 4 and the other fast on the lower end of a vertical jack shaft 34 suitably journaled in the upper crank case section 1 and in the base of the cylinder block 21 at the front end of the engine. The jack shaft 34 drives a gear train comprising a small gear 35 fast on said Jack shaft. The sleeve valves 19 are geared together adjacent their lower ends by larger gears 36 surrounding said valves, respectively, and threaded thereon. Set screws 37 lock the gears 36 to the sleeve valves 19. The small gear 35 meshes with the gear 36 of the front end sleeve valves 19. The gears 36 are suitably accommodated in the base of the cylinder block 21. The jack shaft 34, gearing 32, 33 and gear 35 may be duplicated at the other end of the engine, the gear 38, corresponding to the gear 35, meshing with the gear 36 on the rear end sleeve valve 19, as will be understood. The gears 35, 36, 38 are driven in the direction indicated by the arrows in Figure 3.

The cylinders 20, cylinder heads 24 and sleeve valves 19 are ported as follows:

A pair of vertically elongated, slot-like, fuel-intake ports 39 are provided for each cylinder 20 in the cylinder block 21 upon opposite sides of the latter and upon diametrically opposite sides of the cylinder. The intake ports 39 are arranged tangentially of the cylinder 20 to increase turbulence of the fuel in the cylinder under suction, the advantage of which will be manifest. For each cylinder 20 there is also provided in the cylinder block 21 a pair of supercharge inlet ports 40, similar to intake ports 39, and similarly arranged but succeeding the intake ports 39 as regards the direction of rotation of the sleeve valve 19. The supercharge inlet ports 40 are tangentially arranged in the cylinder block 21 for the same purpose as intake ports 39. Also, for each cylinder 20, there is provided in the cylinder block 21 a pair of exhaust ports 41 constructed and arranged similarly to ports 39, 40, but wider and in advance of the fuel intake ports 39 as regards the direction of rotation of the sleeve valve.

Each cylinder head 24 and sleeve valve 19 is provided therein with a pair of radial, diametrically opposite scavenging ports 42 extending from the combustion chamber 29 in substantially horizontal alignment with the terminals of the spark plug 28 and which, under each revolution of the cylinder head and sleeve valve, registers with a pair of diametrically opposite ports 43 provided in the cylinder 20, all for a purpose presently seen.

Each sleeve valve 19 is provided with diametrically opposite, vertically spaced series of ports 44 therein designed under rotation of the valve to be registered with the exhaust, intake and supercharge inlet ports 41, 39, 40 successively. Adjacent the bottom end thereof, each sleeve valve 19 is provided below the lowest limit of travel of the piston, at 90° intervals with ports 45 which are designed to register with lateral crank case intake and outlet ports 46, 47 extending through the upper crank case section 21 and arranged, a pair of each on each side of each cylinder 20, all for a purpose presently apparent.

A dual intake manifold is provided, with horizontal branches 48 upon opposite sides of the

cylinder block 21, respectively, and which embodies upwardly inclined nipples 49 suitably arranged so that each branch communicates with the intake ports 39 on one side of the cylinder block 21.

A dual exhaust manifold with horizontal branches 50 on opposite sides of the cylinder block 21 is provided with nipples 51 whereby each branch communicates with the exhaust ports 41 on one side of said cylinder block 21.

A particular feature of my improved engine is a supercharge unit including a dual supercharge inlet manifold having horizontal branches 52 disposed upon opposite sides of the cylinder block 21, respectively, with downwardly inclined nipples 53 establishing communication between each branch and the supercharge inlet ports 40 on each side of the cylinder block 21. As best shown in Figure 2, the beforementioned ports 43 in the cylinders 19 open into the nipples 53 of the supercharge manifold branches 52 and for a purpose presently seen.

An oil separator 54 is provided on one end of each branch 52 of the supercharge inlet manifold and which comprises a longitudinally tapered casing 55 having a flat larger end 56, the branch 52 extending part way into said casing axially thereof, through said end. A series of baffle plates 57 are mounted on the branch 52 in the casing 55 and are spaced along the branch, said plates being of different diameter and suitably designed for collecting oil thereon to separate the same from gas fed into the casing. A pair of manifold pipes 58 extend along the sides 30 of the cylinder block 21 one on each side and one of which communicates with ports 46 and the other with ports 47, on each side of the block 21. Crank case discharge pipes 59 extend upwardly from the manifold pipe 58 for the ports 46 to the oil separator casings 55 and opens therein at one side of the same and into the larger ends thereof. The manifold pipes 58 for the ports 47 are connected to the carburetors, not shown, through the manifold branches 48, by 40 risers 60.

Oil separated in the casings 55 discharges through a pair of oil discharge lines 61 depending from the bottoms of said casings at the larger ends thereof and leading to a pair of oil storage tanks 62 located at opposite sides of the crank case of the engine. The oil storage tanks 62 are connected at the bottoms thereof by a pair of lateral fuel lines 63 to an oil feed manifold pipe 64 extending horizontally under the crank case 50 longitudinally and centrally thereof. Risers 65 extend upwardly from said pipe 64 through the bottom of the crank case into and through the crank shaft bearings 8. Radial ports 66 in the intermediate portions 7 of the crank shaft provide 60 for forced feed of oil from the risers 65 into said portions 7 and out of the same to said bearings 8. The end bearings 3' are lubricated by oil from the crank case in the usual manner. The wrist pins 9 and cranks 5 are provided with diagonal oil ducts 67 communicating with the intermediate hollow portions 7 of the crank shaft 4, whereby oil is fed from the portions 7 to the wrist pin bearings.

The intake manifold branches 48 are designed 70 to draw fuel from a primary carburetor supplying a higher than chemically correct mixture, which is to say a rich mixture, for easy starting and smooth running at slow speeds. The supercharger manifold branches 52 are designed to be supplied from a secondary carburetor supplying

a chemically correct air gas mixture for greater power at higher speeds and for increasing the speed of combustion thus making higher speeds possible. Since the carburetors form, per se, no part of the invention, it has not been deemed necessary to illustrate the same.

The operation of my improved engine will now be described with particular reference to Figures 11 to 17, illustrating diagrammatically the operations occurring in connection with one piston 13, sleeve valve 19 and cylinder 20, at different phases in a cycle of operation of the crank shaft 4.

As illustrated in Figure 11, at approximately 5 degrees before upper dead center of a crank shaft 5, the sleeve valve 19 rotates the ports 44 so that they begin to register with the intake ports 39 of the cylinder 20 to open said ports 39. The intake ports 39 remain open until the crank 5 reaches approximately 50 degrees past horizontal center position, thus drawing in gas from the primary carburetor. During this phase of operation ports 42 in cylinder head 24 are closed. During this phase, as shown in Figure 12, ports 44 move past intake ports 39 and a port 45 in sleeve valve 19 registers with a crank case intake port 46 from horizontal center to lower dead center, ports 42 still remaining closed.

At this point, as shown in Figure 13, ports 44 register with supercharge inlet ports 40 and gas under pressure in the supercharger manifold, for reasons presently seen, is forced into the cylinder 20 above the piston 12 with a swirling action around the walls of the sleeve valve 19 and the combustion chamber 29.

At 30 degrees past bottom dead center of the crank shaft 5, as shown in Figure 14, the ports 44 pass supercharge inlet ports 40 and close same during the compression stroke. As the concave top piston 12 approaches the cylinder head 24, it drives the gas inwardly into the combustion chamber 29, thus providing for turbulence of gases in said chamber, high compression, and at the same time reducing the action of heat on the cylinder walls and sleeve valve walls during initial combustion.

The power stroke now takes place, at the end of which, with the crank 30 degrees before lower dead center, the ports 44 register with the exhaust ports 41 which are thus opened and remain open, as shown in Figure 15, until the crank reaches 5 degrees past upper center, as in Figure 16.

At 90 degrees past lower dead center, as shown in Figure 16, ports 42 in cylinder head 24 begin to open to ports 45 and admit a cool mixture under pressure from supercharger manifold branches 53, which mixture blows over the spark plug terminal cooling the same and also blows downwardly into combustion chamber 29 driving out burned gases as the piston rises forcing exhaust gases from the combustion chamber so that at the end of the exhaust stroke the combustion chamber is filled with cool gas air mixture instead of hot burned gases. This constitutes a scavenging operation eliminating such hot gases, and adding to efficiency in operation for reasons which will be manifest.

On the compression, upstroke, as shown in Figures 14, 15, 16 and 17, ports 45 in sleeve valve 19 open to crank case intake ports 47 so that fuel mixture is sucked from the carburetor manifold 48 into the crank case. On the down stroke, as best shown in Figures 12, 13, ports 45 open to crank case outlet ports 46 and the fuel mixture in the crank case is forced through pipes 59 and 75

into oil separator casings 55. Here the oil picked up by the mixture in the crank case is separated from the gas, by centrifugal action, since it is forced into the casing 55 at one side thereof, and also by impact with baffle plates 57. This separation leaves in the casings 55 only a fine oil mist and gas air mixture to be fed to the supercharger intake manifold branches. The separated oil goes into the motor bearings by way of the pipes 61 and tanks 62.

As will be seen, for each power stroke of the piston, there are two charges of gas air mixture pumped from the crank case into the supercharger inlet manifold. Thus, at high speeds or at high altitudes maximum pressure in the supercharger intake manifold is maintained. Oil separated by the oil separator passes into the oil tanks 62 under the same pressure as the gas pressure in the supercharger manifold. This oil is delivered under such pressure to the motor bearings without the use of a mechanical oil pump.

As will be seen, the spark plugs 28 revolve with the cylinder heads 24 and sleeve valve. The electrodes 68 are formed with crank-like upper terminals 69 which revolve past a bus bar 70, comprising a charged line, from the battery or other source of electrical energy.

The foregoing will, it is believed, suffice to impart a clear understanding of my invention, together with the advantages thereof.

Manifestly, the invention, as described, is susceptible of modification, and right is herein reserved to all such modifications falling within the scope of the subjoined claims.

35. What I claim is:

1. In an internal combustion engine, a crank case, a crank shaft in said case, cylinders in line on said case, sleeve valves rotatable in one direction in said cylinders, reciprocating pistons in 40 said valves and operatively connected to said crank shaft, diametrically opposite series of ports in each cylinder, each series comprising an exhaust port, a fuel intake, and a supercharge inlet port arranged successively in each series in the order named and in the direction of rotation of said valves, diametrically opposite series of vertically spaced ports in the sleeve valves, and operating connections between said crank shaft and valves for rotating the series of ports therein past 50 the series of ports in said cylinders.

2. In an internal combustion engine, a crank case, a crank shaft in said case, cylinders in line on said case, sleeve valves rotatable in one direction in said cylinders, reciprocating pistons in 55 said valves and operatively connected to said crank shaft, diametrically opposite series of ports in the side walls of each cylinder, each series comprising an exhaust port, a fuel intake, and a supercharge mixture inlet port arranged successively in each series in the order named and in the direction of rotation of said valves, diametrically opposite series of vertically spaced ports in the sleeve valves, and operating connections between said crank shaft and valves for rotating the 60 series of ports therein past the series of ports in said cylinders at the rate of one power stroke to two charges of gas-air mixture, said connections comprising reduction gearing.

3. In an internal combustion engine, a crank case, a crank shaft in said case, cylinders in line on said case, sleeve valves rotatable in one direction in said cylinders, reciprocating pistons in said valves and operatively connected to said crank shaft, diametrically opposite series of ports in the side walls of each cylinder, each series comprising

ing an exhaust port, a fuel intake, and a supercharge mixture inlet port arranged successively in each series in the order named and in the direction of rotation of said valves, diametrically opposite series of vertically spaced ports in the sleeve valves, and operating connections between said crank shaft and valves for rotating the series of ports therein past the series of ports in said cylinders at the rate of one power stroke to two charges of gas-air mixture, dual supercharge supply manifolds for supplying a carbureted mixture to the supercharge inlet ports upon opposite side of said side walls of the sleeve valve and cylinder, respectively, heads for said cylinders, and means to intermittently establish communication between said manifolds and said cylinders through said ports in said side walls.

4. In an internal combustion engine, a crank case, a crank shaft in said case, cylinders in line on said case, sleeve valves rotatable in one direction in said cylinders, reciprocating pistons in said valves and operatively connected to said crank shaft, diametrically opposite series of ports in the side walls of each cylinder, each series comprising an exhaust port, a fuel intake, and a supercharge mixture inlet port arranged successively in each series in the order named and in the direction of rotation of said valves, diametrically opposite series of vertically spaced ports in the sleeve valves, and operating connections between said crank shaft and valves for rotating the series of ports therein past the series of ports in said cylinders at the rate of one power stroke to two charges of gas-air mixture, dual supercharge supply manifolds for connecting a carburetor to the supercharge inlet ports upon opposite sides of said side walls of the sleeve valve and cylinder, respectively, heads for said cylinders, and means to intermittently establish communication between

said manifolds and said cylinders through said side walls, said side walls revolving with said sleeve valves.

5. In an internal combustion engine, a crank case, cylinders arising from said case, rotary sleeve valves in said cylinders, reciprocating pistons in said valves, means to feed a supercharge fuel mixture into said sleeve valves under suction created by said pistons and controlled by rotation of said valves at the rate of one power stroke to two of gas-air mixture.

6. In an internal combustion engine, a crank case, cylinders arising from said case, rotary sleeve valves in said cylinders, reciprocating pistons in said valves, means to feed a supercharge fuel mixture into said sleeve valves under pressure created by said pistons and controlled by rotation of said valves at the rate of one power stroke to two of gas-air mixture, and means to feed the supercharge fuel mixture to said crank case under suction created by said pistons to cool the pistons from the bottoms thereof and the lower parts of the sleeve valves.

7. In an internal combustion engine including means providing carbureted mixture, a crank case, cylinders on said crank case, pistons in said cylinders, a supercharger for feeding said carbureted mixture to said cylinders, an oil supply tank communicating with said crank case, means to feed said carbureted mixture to said crank case under suction created by said pistons, means to expel the mixture from said crank case under compression created by said pistons in said crank case, and means to separate oil from said expelled mixture and to deliver the same to said tank, said first means comprising rotary controlling valves in said cylinders.

FRED L. KNOWLES.
